Des. 198,091
Patented Apr. 28, 1964

198,091

FIGURE OF A HEAD

Carol M. Bonner, 10547 23rd NE, Seattle, Wash.

Filed Oct. 14, 1963, Ser. No. 76,973

Term of patent 14 years

(Cl. D34—4)

Fig. 1.

Fig. 2.

Fig. 3.

Fig. 4.

Fig. 5.

Fig. 6.

FIGURE 1 is a top plan view of the figure of a head, showing my new design wherein the hair portion is short to represent a male;

I claim:

The ornamental design for the figure of a head, substantially as shown and described.
